UNITED STATES PATENT OFFICE.

CHARLES A. GOYNE, OF ASHLAND, PENNSYLVANIA, ASSIGNOR OF THREE-FOURTHS TO GOYNE STEAM PUMP CO., OF ASHLAND, PENNSYLVANIA, A CORPORATION OF PENNSYLVANIA.

DUPLEX STEAM-PUMP.

SPECIFICATION forming part of Letters Patent No. 776,318, dated November 29, 1904.

Application filed April 1, 1904. Serial No. 201,128. (No model.)

To all whom it may concern:

Be it known that I, CHARLES A. GOYNE, a citizen of the United States, residing at Ashland, in the county of Schuylkill and State 5 of Pennsylvania, have invented new and useful Improvements in Duplex Direct-Acting Steam-Pumps, of which the following is a specification.

This invention relates to duplex direct-acting steam-pumps, and has to do more particularly with an improved construction of the main valve and of a cut-off valve coöperating therewith and to improvements in the mechanism for operating said main and cut-off 15 valves.

The objects had in view are to insure a uniformly full stroke of the piston, to provide for an absolute cut-off of the steam at any desired point in the stroke of the piston and independently of the movement or length of stroke of the main valve, whereby the amount of steam supplied may be varied in accordance with the speed at which the engine is running, and to provide for causing the steam entering 20 through respective cut-off ports of the main valve to pass only in given directions to the steam-cylinder.

The above constitute the main objects of the invention, in the attainment of which, however, 30 various novel details of construction and combinations and operations of parts are involved which cannot be intelligibly set forth in general terms at this point, but a knowledge of which can be clearly gained from the detailed description following, taken in connection with the accompanying drawings.

That which I claim as my invention will be clearly indicated in the claims following the detailed description of the invention.

To the end that my invention may be clearly understood by those skilled in the art to which it relates I have illustrated the same in the accompanying drawings, in which—

Figure 1 is a top plan view of my improved 45 duplex direct-acting steam-pump. Fig. 2 is a sectional side elevation, the section being taken through one of the cylinders. Fig. 3 is a top plan view of one of the cylinders, show-

ing its valve-seat. Fig. 4 is a detail plan view illustrating a set of valves for one of the cylinders, together with their operating mechanism. Fig. 5 is a transverse sectional view taken through a valve-chest of one of the cylinders. Figs. 6, 7, and 8 are detail views of one of the slide-valves. Fig. 9 is a detail perspective view 55 of one of the cut-off valves. Figs. 10 and 11 are sectional details illustrating two different positions of the slide-valve of one of the cylinders with relation to the ports in said cylinder, and Fig. 12 is a perspective diagrammatic view illustrating the connections between the pistons and the valves.

Referring now to the drawings, 1 2 indicate, respectively, the two cylinders of the steam end of the pump, and 3 4 the pump-cylinders, 65 which are respectively connected to their steam-cylinders, as usual, by means of the bars 5. As the invention has only to do with the steam end of the pump, the following description will be confined thereto, and as the 70 cylinders 1 2, together with their respective valve mechanisms, are identical in construction a description of one will apply equally well to the other, and this description I will now proceed to give.

Referring to Fig. 2, it will be seen that the cylinder 1 is provided with a steam-chest 6, in which the main valve 7 is located. 8 indicates the valve-seat, which, as usual, is provided by a flattened portion formed on the upper side of the cylinder, and from this valve-seat lead the ports communicating with the interior of the cylinder. According to this invention I provide two ports leading to each end of the cylinder. These ports are indicated, respectively, by 9 and 10 and 11 and 12. The ports 9 and 11 are relatively wide as compared with the ports 10 and 12 and communicate with the interior of the cylinder at some distance from the respective ends thereof. 90 The ports 10 and 12 are approximately one-fourth of the width of the ports 9 and 11 and communicate with the interior of the cylinder at the extreme ends thereof, respectively. A partition-wall 13 separates the two ports. 14 95 indicates the exhaust-port, which is located

between and in line with the ends of the ports 9 and 11, which terminate in the valve-seat.

I have illustrated in detail the construction of the slide-valve in Figs. 6, 7, and 8 and will now proceed to describe the same. Said slide-valve is, as shown, rectangular in shape and on its upper side is provided near opposite sides with cut-off ports 15 and 16 and central of its upper side with a steam-cavity 17 for the purpose of balancing an equal area of the cut-off valve, as hereinafter explained. On the under side of the valve, as shown in Fig. 7, near what I term "opposite" ends of the valve, are provided elongated steam-ports 18 and 19, and these ports are separated from each other and from one of the cut-off ports 15, 16 by means of a partition 20, which extends diagonally across the interior of the valve from the end of one cut-off port 15 to the opposite end of the other cut-off port. The valve 7 is otherwise hollow. The provision of the partition 20, it will be seen, insures that steam entering through the port 16 can only pass out through the port 19 and steam entering through the cut-off port 15 can only pass out through the steam-port 18. The under side of the main valve 7 is also provided with an exhaust-cavity 21, which is located to one side of the longitudinal center of said valve, leaving a blank surface 22 for a purpose to be presently explained. On the top of the valve 7 and extending transversely thereof in parallel relation are guide-ribs 23, between which the cut-off valve 24 slides. Disregarding for a moment the provision of the cut-off valve, the operation of the main valve 7, in connection with the ports 9 and 10 and 11 and 12, will now be described.

In its position on the valve-seat 8 the blank surface 22 of the valve 7 is designed to control the openings of the narrow ports 10, 12 and of the wide ports 9, 11, terminating in the valve-seat, and the steam-ports 18 and 19 of said valve are designed to open communication for the passage of steam through said ports 9, 11 and 10, 12. The exhaust-cavity 21 of the valve, however, does not extend to the ports 10 and 12, and hence communication with the exhaust-port 14 is only afforded through the ports 9 and 11. The purpose of this construction is as follows:

Assuming the piston 25 in Fig. 2 to be moving to the right, steam will be exhausting through the port 9 to the exhaust-port 14, the two being brought into communication by the exhaust-cavity 21 of the valve. When the piston 25 has reached a position to cover the opening of the port 9, the exhaust ceases, as the blank surface 22 of the valve will then be covering the port 10. Steam will therefore be trapped in the end of the cylinder and afford a cushion to prevent the abrupt termination of the stroke of the piston, and thus avoid jarring of the engine and consequent wear and tear. As the valve 7 is moved to

permit steam to enter the ports 9 and 10 it will be seen that the steam will first enter through the port 10, as the port 9 will be closed by the piston. By this construction I provide for imparting an initial motion to the piston with a small volume of steam, which is very desirable in direct-acting pumps, and after a slight forward movement the piston 24 uncovers the port 9, so that steam now enters in full volume through both ports 9 and 10, causing the piston to move to the end of its stroke near the opposite end of the cylinder. At said opposite end of the cylinder the same operation will take place—that is to say, the steam will exhaust through the port 11 until the piston moves to the position to cover said port, and the blank surface 22 covering the port 12 steam will be trapped and cushion the piston. The valve 7 being moved to open communication with the ports 11 and 12 through the port 18 of the valve, steam will first pass through the port 12 and impart motion to the piston, and after a slight forward movement port 11 will be uncovered and the full volume of steam will enter the cylinder through both ports 11 and 12.

I have arranged to cause the slide-valve of the cylinder 1 to be operated by the motion of the piston-rod of cylinder 2 and the slide-valve of cylinder 2 to be operated by the motion of the piston-rod of cylinder 1, while the cut-off valve of each cylinder is operated from the motion of its own piston-rod, and I will now proceed to describe the mechanism for accomplishing this operation.

Mounted on each of the outer bars 5, connecting the steam-cylinders and pump-cylinders, as before referred to, is a bracket 26, 26^a, supporting uprights 27, which afford bearings for two transverse rods 28 and 29, which are disposed one directly over the other in parallel relation. The respective piston-rods 30, 31 are each provided with a cross-head 32, 33, and on the outer side of one of said cross-heads is pivotally mounted one end of a link 34, to the opposite end of which is pivotally connected one end of a lever-arm 35, the opposite end of which is fixedly secured to the lower rod 29. The rod 29 is adapted to operate the valve of the cylinder 2, and hence toward the opposite end of said rod from that just referred to and in front of the cylinder 2 said rod is provided with a crank 36, to the free end of which crank is pivotally connected an arm 37, the opposite end of which is pivotally mounted in a bearing 38, through the medium of a pin 39, passed through said arm, and secured in the bearing 38 by a nut 40. The bearing 38 forms part of a sleeve 41, which is mounted to slide on the valve-rod 42 a greater or less distance determined by means of adjustable collars 43, mounted on said valve-rod on either side of said sleeve. By the provision of the adjustable collars 43 the sleeve 41 will slide a determinate distance in

either direction before striking one or the other of the collars to operate the slide-valve, as will be understood.

44 indicates an arm secured to the bracket 5 26 and affording in its free end a bearing 45 for the outer end of the valve-rod 42. The opposite end of the valve-rod is provided with a rectangular head 46, which is adapted to be inserted in a slot 47, formed in one end of the 10 valve and to be secured therein by means of a plate 48, screwed to the outer face of said valve and provided in one side with a recess 50, extending to about the center of the plate, which encircles the rod 42 in such manner 15 that the plate shall bear against the inner side of the head 46 and hold it within the slot 47, as clearly shown by Fig. 4. It will thus be seen as the piston-rod 31 reciprocates the rod 29 will be rocked through the medium of the 20 link 34 and lever-arm 35 and that this rocking movement of the rod 39 will cause the crank 36 to reciprocate the arm 37 back and forth, whereby through the medium of the sleeve 41 and the collars 43 the valve-rod 42 25 will be correspondingly reciprocated and slide the valve 7 of the cylinder 2 back and forth to alternately cover and uncover the ports 9, 10, 11, and 12 in the manner heretofore described.

The rod 28 is adapted to operate the valve 30 of the cylinder 1, and to this end the cross-head 32 is provided with a link 51, the outer end of which is pivotally connected to the lever-arm 52, the opposite end of which is fixedly secured to the shaft 28. Said shaft 28 35 is provided with a crank 53, to which is connected an arm 54, pivotally secured to a sleeve 55, mounted on the valve-rod 56 in the same manner as described with reference to the corresponding parts of the cylinder 2. Through 40 the medium of the parts described it will be seen that on the reciprocation of the piston 30 the shaft 28 will be rocked to move back and forth the valve 7 of cylinder 1.

The cut-off valve has previously been briefly 45 referred to and indicated by the numeral 24. This valve comprises a flat piece or plate of metal designed to slide on top of the valve 7 between the guide-ribs 23, as previously stated, and at opposite ends is provided with 50 upwardly-projecting portions 57 58. Mounted to move in the space between the projections 57 58 are two blocks 59 60, which are respectively mounted on right and left hand screw-threaded portions of a rod 61. Said 55 rod extends transversely across the entire width of each cylinder and on one of its ends has loosely mounted, on a reduced portion thereof, a sleeve 62, which is held in place on the rod by a nut 63. Mounted on each valve- 60 chest is a bracket-arm 64, pivotally mounted on the outer end of which is a bell-crank lever 65, one arm of which is pivotally connected to a rod 66 and the other arm of which is connected, through the medium of a link 67, 65 with the sleeve 62. Secured to the rod 28,

which operates the valve of the cylinder 1, is a crank 68, to which is pivotally connected the other end of the rod 66, one end of which has been described as being connected to the bell-crank lever 65. Secured to the rod 29, 70 which operates the valve of the cylinder 2, is a crank 69, to which is secured one end of a rod 70, similar to the rod 66 and connected to similar mechanism for operating the cut-off valve of the cylinder 1. The rod 61 is provided on its opposite end to that described as being secured in the sleeve 62 with a groove 71, which is adapted to receive a feather 72, formed on the inner side of the hub 73 on a hand-wheel 74. The said hub 73 is mounted 75 in a bearing 75, supported from the side of each valve-chest, and a clamping-screw 76 is provided in the bearing 75 for preventing the hand-wheel from turning after it has once been adjusted. The rod 61, however, is always free to reciprocate in the hub 73. By loosening the clamping-screw 76 and turning the hand-wheel 74 the hub 61 may be turned, and this movement will cause the blocks 59 80 and 60 to be moved closer together or farther apart, as the case may be, due to the fact, as stated, that one block is mounted on a right-hand screw-threaded portion of the rod, while the other block is mounted on the left-hand screw-threaded portion of the rod. The 85 object of adjusting these blocks, which, of course, are intended to come into contact with the projections 57 and 58 of the cut-off valve, is to determine the point of cut-off, as the farther the blocks are apart the quicker the cut-off will be and the nearer they are together the slower the cut-off will be. It will be seen, moreover, that as the blocks 59 and 60 are 90 slidably mounted on top of the cut-off valve 24 said cut-off valve may be moved by the 95 slide-valve 7 transversely to the line of movement of said blocks without in any manner affecting the ability of said blocks to operate the cut-off at the desired moment, so that the movement of the cut-off valve is absolutely independent of the movement of the main valve, and such cut-off can be arranged to take place at any desired point in the stroke of the piston 100 irrespective of the relative movement or position of the slide-valve. This is further due 105 to the fact that while each piston-rod operates the cut-off valve of its own cylinder its main valve is operated by the piston-rod of the other cylinder. In the movement of either piston-rod the rod 66 or 70, as the case may 110 be, is reciprocated by means of the crank 68 or 69, and through the medium of the bell-crank lever 65 and the link connection 67 with the sleeve 62 the rod will be reciprocated back and forth, the blocks 59 and 60, respectively, 115 coming alternately into contact with the projections 57 and 58 of each cut-off valve to reciprocate said cut-off valve. As said cut-off valve is thus reciprocated it alternately opens 120 and closes the cut-off ports 15 and 16 in the 125 130

main valve. As the cut-off port 15 is opened steam enters from the valve-chest 6 through said port and passes out of the steam-port 18 through the ports 11 and 12 to the front end 5 of the cylinder, and as the port 16 is opened steam passes through said port to the port 19 and thence through the ports 9 and 10 to the back end of the cylinder.

The provision of the recess 17 in the top of 10 main valve permits steam to enter beneath the cut-off valve, and thus operate to partially balance said valve and reduce its friction.

By referring to Fig. 2 it will be seen that the valve-seat proper projects above the surrounding 15 surface of the cylinder, the projecting portion being indicated by the numeral 77, and it will also be seen that this projecting portion is not coextensive with the stroke of the valve—that is to say, when the valve is moved to the extreme 20 position in either direction there will be an overhanging portion of the valve extending beyond the raised portion 77. In other words, in one movement of the valve the steam-port 18 will pass beyond the valve-seat, and steam may enter from the steam-chest through the port 18 into the interior of 25 the valve, and hence assist in balancing the valve. Before the valve is moved to its extreme 30 position in the opposite direction the port 19 will pass beyond the valve-seat and steam can enter from the valve-chest through the cut-off ports 15 or 16. The partition 20, however, prevents all steam 35 from entering the cylinder, except such as enters from the valve-chest through the cut-off ports 15 or 16.

78 indicates the steam-supply pipes communicating with the valve-chest, each of said pipes having a valve 79 and communicating 40 with a common source of steam-supply 80.

81 represents the pipes for exhaust-steam.

A steam end constructed according to my invention as above described will insure regularity and uniformity of stroke of the piston, 45 great economy in the use of steam, and provides for a smooth-running machine, all of which are highly-important objects to be attained in this art.

Having thus fully described my invention, 50 what I claim as new, and desire to secure by Letters Patent, is—

1. In an apparatus of the class described, in combination with a cylinder provided with a main valve carrying a cut-off valve, means for 55 operating said main valve without affecting the time of action of its cut-off valve, and means, independent of the main-valve-operating means, for operating said cut-off valve to effect the cut-off at predetermined intervals 60 independently of the movement and irrespective of the position of said main valve.

2. In an apparatus of the class described, in combination with a cylinder provided with a main valve carrying a cut-off valve, means for 65 operating said main valve without affecting

the time of action of the cut-off valve and means, independent of the main-valve-operating means, for moving said cut-off valve in a direction at right angles to the movement of said main valve to effect the cut-off at predetermined intervals independently of the movement and irrespective of the position of said main valve. 70

3. In an apparatus of the class described, in combination with two cylinders each of which is provided with a main valve carrying a cut-off valve, means for operating each main valve from the piston of the other cylinder and without affecting the time of action of its cut-off valve, and means for operating each cut-off 75 valve from the piston of its own cylinder to effect cut-off at predetermined intervals independently of the movement and irrespective of the position of said main valves. 80

4. In an apparatus of the class described, in combination with two cylinders each of which is provided with a main valve carrying a cut-off valve, means for operating each main valve from the piston of the other cylinder and without affecting the time of action of its cut-off 90 valve, and means for operating each cut-off valve from the piston of its own cylinder in a direction at right angles to the movement of its main valve to effect cut-off at predetermined intervals independently of the movement and irrespective of the position of said main valves. 95

5. In an apparatus of the class described, in combination with a cylinder provided with a main valve carrying a cut-off valve, means for moving said main valve without affecting the time of action of the cut-off valve, and adjustable means, independent of the main-valve-operating means for moving said cut-off valve to effect absolute cut-offs of the steam 100 at any desired point in the stroke of the piston irrespective of the position of said main valves. 105

6. In an apparatus of the class described, in combination with a cylinder provided with a main valve having a cut-off valve slidably mounted thereon and adapted to move in a direction at right angles to the movement thereof, means for moving said main valve without affecting the time of action of the cut-off valve, and means independent of the main-valve-operating means, and including adjustable contacts, for moving said cut-off valve independently of the movement of said main valve. 115

7. In an apparatus of the class described, in combination with two cylinders each of which is provided with a main and a cut-off valve, means operated by the movements of the pistons in the two cylinders for effecting movement of the main valves without affecting the time of action of the cut-off valves, and movement of each cut-off valve independently of the movement of its main valve, the main valve of one cylinder being operated from the piston of the other cylinder, and each cut-off valve 120 125 130

being operated from the piston of its own cylinder.

8. In an apparatus of the class described, in combination with two cylinders each of which 5 is provided with a main and a cut-off valve, means operated by the piston of each cylinder for operating the main valve of the other cylinder without affecting the time of action of the cut-off valve thereof and for operating each 10 cut-off valve independently of the movement of its main valve.

9. In an apparatus of the class described, in combination with two cylinders each of which is provided with a main and a cut-off valve, 15 means operated by the movement of the piston of each cylinder for operating the main valve of the other cylinder, and means for effecting an absolute cut-off of the steam at any desired point in the stroke of each piston by said cut- 20 off valves irrespective of the relative position of the main valve of said piston.

10. In an apparatus of the class described, in combination with two cylinders each of which is provided with a main valve and a 25 cut-off valve and with a piston-rod and piston, a pair of rock-shafts, one of which is operated by the piston-rod of each cylinder to move the main valve of the other cylinder, and adjustable means for moving said cut-off valves 30 comprising a rod provided with right and left hand screw-threads and having means for turning it, contact-blocks mounted on the screw-threaded portions of said rod and adapted to engage opposite ends of said cut-off valve, a 35 crank on each of said rock-shafts, rods connected to said cranks, and lever mechanism operatively connecting said rods with the rods of the cut-off valves.

11. In an apparatus of the class described, 40 in combination with a cylinder having a main valve, and a cut-off valve slidably mounted thereon, means for moving said cut-off valve comprising a rod provided with right and left hand screw-threads and having in one end portion a longitudinal groove, a hand-wheel having a hub encircling said rod and provided with a feather inserted in said groove, a bearing for said hub, means for locking said hub against rotation, adjustable contacts mounted 45 on the screw-threaded portions of said rod and adapted to engage opposite end portions of said cut-off valve, and means for reciprocating said rod.

12. In an apparatus of the class described,

a main valve provided with cut-off and steam 55 ports located, respectively, at the ends and sides of said valve, and a diagonal partition separating one cut-off port and steam-port of the valve from the other cut-off and steam port. 60

13. In an apparatus of the class described, in combination with a cylinder having a piston and a valve-seat, steam-ports terminating in said valve-seat and communicating with the interior of the cylinder, a main valve on said cylinder having cut-off and steam ports located, respectively, at the ends and sides of 65 said valve, a diagonal partition separating one cut-off and steam port of the valve from the other cut-off and steam port, a cut-off valve 70 mounted on said main valve and means for operating said valves.

14. In a steam-pump, in combination with a cylinder having a piston and a valve-seat, and provided with main and auxiliary ports 75 leading from said valve-seat and communicating with said cylinder at different distances from the ends thereof, a main valve on said valve-seat having cut-off and steam ports and provided with a blank surface adapted to cover 80 and uncover said main and auxiliary ports and with an exhaust-cavity communicating only with said main ports, a partition separating one cut-off port and its steam-port of the valve from the other cut-off port and steam-port, a 85 cut-off valve mounted on said main valve, and means for operating said valves.

15. In an apparatus of the class described, a cylinder provided with a valve-seat extending above the surrounding surface of the cylinder, a slide-valve mounted on said seat and having a greater area than said valve-seat and having ports located at the ends and sides of 90 said valve, a steam-chest inclosing said slide-valve, means for reciprocating said valve 95 whereby in operation its ports will alternately be moved beyond each side of the valve-seat to permit steam to enter the valve and thus balance it, and a diagonal partition in said valve separating the respective sets of ports 100 thereof from each other.

In testimony whereof I have hereunto set my hand in presence of two subscribing witnesses.

CHARLES A. GOYNE.
